UNITED STATES PATENT OFFICE.

FRED EUGENE BRIGHT, OF PHILADELPHIA, PENNSYLVANIA.

MECHANICAL MOVEMENT.

1,074,832.

Specification of Letters Patent.

Patented Oct. 7, 1913.

Application filed March 4, 1911. Serial No. 612,212.

To all whom it may concern:

Be it known that I, FRED EUGENE BRIGHT, a citizen of the United States, residing at Philadelphia, in the county of Philadelphia and State of Pennsylvania, have invented certain new and useful Improvements in Mechanical Movements, of which the following is a specification, reference being had therein to the accompanying drawing.

10 My invention relates to mechanical movements and more particularly to that class thereof wherein a constant rotary motion may be converted into an intermittent reciprocating motion. In the form illustrated 15 and described, it is shown as applied to a keyboard mechanism, such for instance as is employed in linotype machines to govern the release of the matrices from the magazine. Obviously, however, it may be used 20 in various ways and in different embodiments, and I do not desire to limit myself to any specific form except in so far as such limitations are specified in the claims.

In some respects the mechanism herein 25 embodied is of substantially the same character in construction and mode of operation as those presented for instance in United States Letters Patent to Ottmar Mergenthaler, No. 531,266, dated December 18, 1894, 30 and Philip T. Dodge, No. 530,931, dated December 18, 1894. In these patents are disclosed escapement actuating means, wherein the rods or bails are operated by levers which in turn are provided with cams journaled 35 thereon. Each cam is arranged so that upon the release of the operating lever it is brought into engagement with a constantly driven roll in such manner that it causes a complete rotation of the cam. This 40 action effects the two-fold result; first, of reciprocating the rod or bail so as to actuate the escapement, and second, by reason of the shape of the cam, of restoring the connected lever to its normal position. In the present 45 instance, instead of such a cam, I employ a gear or driven member which is also normally held out of engagement with the roll or driving member. The driven member is not directly connected to an operating lever, 50 as in the previous instance, but is mounted so as to be capable of motion to and from the driving member, it being normally held out of engagement therewith by a separate and independent device upon which it rests 55 in its inoperative position. Specifically, the normal contact between the holding device

and the driven member is secured by an eccentrically located part on the latter, which in inoperative and disengaged position rests on the former. When the holding device 60 is tripped in the manner subsequently to be described, the driven member engages with the driving roll and is thereby rotated, and during its movement the eccentrically located part contacts with another portion of 65 the holding device in such manner as to restore it to its original position and thus to leave it in readiness to reengage and hold the driven member when the latter comes to rest.

70 Referring to the drawings: Figure 1 is a transverse vertical section through the keyboard of a linotype machine, having my invention applied thereto; Fig. 2 is a sectional front view of a part of the same; Figs. 3, 4 75 and 5 are detail views of the principal parts of the mechanical movement, showing them in successive operative positions; and Figs. 6 and 7 are detail constructional views.

As is usual in linotype machines, the matrices A are stored in the magazine M and their release therefrom is governed by an escapement B, all in the manner well understood in the art. Each escapement is operated by a reciprocated rod or bail I, the exact connection of which to the escapement is immaterial and constitutes no part of the present invention. As is also customary, the machine is provided with a keyboard having a series of keys C, whereby the respective 90 matrices are selected, their delivery being automatically effected through the specific means now to be described. Each key C is held in its upward or normal position by a spring D and is connected by a link E to a pivoted dog or pawl F, which sustains the escapement-rod operating parts in normal or inoperative position. The dog or pawl F is provided with two operative faces or notches 11 and 12, and its throw is limited by the engagement of a projecting pin G (shown in dotted lines in Fig. 1) with the curved slot H (see Fig. 7).

100 Power is transmitted to the respectively selected rod-operating parts by a constantly actuated roll or driving member 2, located in the keyboard mechanism in position to engage and actuate the driven members of the escapement operating devices. This rotational movement of the driving member 2 105 may be imparted to it in any desired manner, as for instance by the belt pulley J.

Each of the rods or bails I is connected to a driven member or gear 3 by a stud 6 located eccentrically thereon, and in such manner that when the gear is caused to rotate, the rod will be reciprocated to operate the corresponding escapement. The gears 3 are located in a bank or series over the driving member 2 and are separated from each other by a corresponding series of supporting and guiding plates K (see Fig. 7). Each of the gears 3 is formed with a projecting hub or boss 4 (see Fig. 6) which in assembled position occupies the vertically elongated slot 5 in the plate K. The effect of this arrangement is to permit not only the rotation of the gear 3 but also a limited radial motion toward and from the driving member 2. Normally the gear 3 is in its uppermost or inoperative position, as shown in Fig. 1, that is to say, with its hub 4 in the upper portion of the vertical slot 5. This relation of the parts is maintained by means of the separate and independent holding device 7 which is pivotally mounted on the plate K. In the form shown, the holding device is provided with two extending branches, an upper arm 8, and a lower arm 9. The lower arm 9 normally rests in the upper notch 11 of the pivoted dog or pawl F previously referred to, and in this position it supports the gear 3 by reason of the engagement therewith of the eccentrically located part 6.

When the key C is depressed, through the connections previously described, the dog or pawl is rocked outwardly and the arm 9 of the holding device 7 is permitted to drop until it enters and engages the lower notch 12, which position of the parts is shown in Fig. 3. The support for the gear 3 being thus removed, it drops into engagement with the driving member 2 and the rotation of the gear is initiated, as indicated by the arrow thereon. This rotary movement continues until the eccentrically located part 6 engages under the upper arm 8 of the holding device 7, thus raising the latter above its normal position. These relations of the parts are shown in Fig. 4. When the arm 9 has been thus removed from the notch 12 of the dog F, the spring D previously referred to restores the dog to its normal position, and as the further rotation of the gear 3 carries the eccentrically located part beyond and out of contact with the upper arm 8, the arm 9 will now descend and again rest in the upper notch 11. The rotation of the gear 3 still proceeds and the eccentrically located part 6 again contacts with the angular arranged upper surface of the arm 9, the effect of which rotation and contact is to withdraw the gear 3 from engagement with the driving member 2. This position of the parts is shown in Fig. 5. The rotation of the gear continues until the driving

and driven members are entirely separated, and even then by momentum, until the eccentrically located part 6 comes into engagement with and is arrested by the stop shoulder 10, when the parts are again in the position indicated in Fig. 1. The cycle of operation is thus complete and has resulted in the reciprocation of the escapement pawl or rod, effecting the delivery of a single matrix. It will be obvious that if the tripping means be held continuously out of action, as for instance by holding the connected key down, the gear 3 will be permitted to engage constantly with the driving member 2, thus resulting in an uninterrupted operation of the escapement or other connected part.

Obviously many variations and changes may be made in the embodiment of my invention without departing from its scope or spirit, and these will suggest themselves to those skilled in the art. Its advantages are numerous and well defined. There can be no slipping between the parts, as in the case of cams, and consequently greater regularity of action results. The mechanism is self-contained, admits of assemblage without screws or rivets, and may be readily placed in operative position within the keyboard frame-work, or in a similar manner connected to any kind of operating or operated mechanism that may be desired or employed. The parts may be cheaply and rapidly manufactured, as they may be made entirely by punches and dies, and preferably from sheet-steel that may be effectively case-hardened so as to make them almost entirely proof against wear. It is also so compact that a single bank or row of the assembled mechanisms will suffice for a standard keyboard.

Having thus described my invention, its construction and mode of operation, what I claim and desire to secure by Letters Patent of the United States, is:

1. The combination with a rotated driving member and a rotatable driven member capable of engaging therewith, of a device to contact with and hold the driven member out of engagement with the driving member, the driven member being independently mounted and movable toward and from both the driving member and the holding device.

2. The combination with a rotated driving member and a rotatable driven member capable of engaging therewith, of a device to contact with and hold the driven member out of engagement with the driving member, the driven member being independently mounted and movable toward and from both the driving member and the holding device, together with means for tripping the holding device.

3. The combination with a rotated driving member and a rotatable driven member capable of engaging therewith, of a device

whereon the driven member directly rests and is thus held out of engagement with the driving member, the driven member being independently mounted and movable toward 5 and from both the driving member and the holding device.

4. The combination with a rotated driving member and a rotatable driven member capable of engaging therewith, of a device 10 whereon the driven member directly rests and is thus held out of engagement with the driving member, the driven member being independently mounted and movable toward and from both the driving member 15 and the holding device, together with means for tripping the holding device.

5. The combination with a rotated driving member and a rotatable driven member capable of engaging therewith, of a device 20 to hold the driven member out of engagement with the driving member, the driven member being independently mounted and movable toward and from both the driving member and the holding device, means for 25 tripping the said holding device, and means connected to the driven member for restoring the holding device to normal position.

6. The combination with a rotated driving member and a rotatable driven member capable of engaging therewith, of a device 30 to hold the driven member out of engagement with the driving member, the driven member being independently mounted and movable toward and from both the driving member 35 and the holding device, means for tripping the said holding device, and means eccentrically connected to the driven member for restoring the holding device to normal position.

40 7. The combination with a rotated driving member and a rotatable driven member capable of engaging therewith, of a device to hold the driven member out of engagement with the driving member, and means 45 for tripping the holding device, the driven member being independently mounted and movable toward and from both the driving member and the holding device, and the said driven member being provided with an eccentrically located part which normally 50 rests upon the holding device and also subsequently contacts therewith to restore it to normal position.

8. The combination with a rotated driving 55 member and a rotatable driven member capable of engaging therewith, of a separate and independent holding device having two extending branches, and means for tripping the holding device, the said driven member 60 being provided with an eccentrically located portion which normally rests upon one of the branches of the holding device, and also subsequently contacts with the other branch thereof to restore the device to normal position.

9. The combination with a rotated driving member and a rotatable driven member capable of engaging therewith, the said driven member being provided with an eccentrically located part, of a two-branched holding device and means for tripping it, the said eccentrically located part of the driven member being also located between the two branches of the holding device so that it normally rests upon one of them and subsequently contacts with the other to restore it to its original position. 70

10. The combination of a rotated driving member, a rotatable driven member mounted to be movable toward and from the driving member and capable of engaging therewith and being rotated thereby, and independent and separate deflecting means to engage said rotating driven member so that its continued rotation shifts and thus disengages it from 80 the driving member.

11. The combination of a rotated driving member and a rotatable driven member mounted to be movable toward and from each other and capable of engagement so 90 that the driven member may be rotated by the driving member, and independent and separate deflecting means to contact with one of said members when in rotary engagement so that its continued rotation relatively moves and thus separates the said members. 95

12. The combination of a rotated driving member and a rotatable driven member mounted to be relatively movable toward 100 and from each other and capable of engagement so that the driven member may be rotated by the driving member, and mechanism adapted to effect the engagement of the driving and driven members, the said mechanism comprising an independent automatic device to contact with one of said rotating members so that its continued rotation relatively moves and thus again separates the said members. 105

13. The combination of the continuously rotated roll, a rotatable gear to be engaged and actuated thereby, a device to contact with and hold the gear in disengaged position, the gear being independently mounted and movable toward and from both the roll and the holding device, and the finger key mechanism for sustaining and releasing the said device, whereby the gear is held normally out of contact with the roll, and the action of the key permits the release of said device and the engagement of the gear with the roll. 115

14. The combination of the constantly rotated roll, a rotatable gear to engage therewith, a device to hold the gear out of engagement with the roll, the gear being independently mounted and movable toward and from both the roll and the holding device, and the gear being provided with a 125 130

- part which normally rests upon the holding device, a dog to sustain the said device, and a finger key and connections from it to the dog.
15. The combination of the driving roll 2, the gear 3, the independent and movable holding device 7 whereon the gear 3 directly rests, and the tripping means F.
16. The combination of the driving roll 2, the gear 3 provided with an eccentrically located part 6, the movable supporting and holding device 7 having the projecting arm 9 whereon the eccentric part 6 normally rests, and the tripping means F for the holding device.
17. The combination of the driving roll 2, the gear 3 provided with an eccentrically located part 6, the holding device 7 whereon the eccentrically located part 6 normally rests, and the tripping means F, the said holding device 7 being formed with a pro-
- jecting arm 8 arranged in the path of the movement of the part 6 whereby the rotation of the gear 3 restores the holding device 7 to its normal position.
18. The combination of the driving roll 2, the gear 3 provided with the eccentrically located part 6, the holding device 7, and the tripping means F, the said holding device 7 being provided with two projecting arms 8 and 9 and the eccentrically located part 6 being arranged between them so that it rests normally on one of them and subsequently contacts with the other to restore the holding device to normal position.
